STRIPING INSTRUMENT

Earl M. Barden, Detroit, Mich., assignor to Packard Motor Car Company, Detroit, Mich., a corporation of Michigan

Application January 28, 1931, Serial No. 511,716

4 Claims. (Cl. 91—62.6)

This invention relates to dispensing devices and more particularly to striping instruments.

One type of striping instrument, now in common use, consists of a body having a gear driven pump operated through means of a roller guide contacting with the work to be operated upon, a nozzle extending from the body and communicating with the pump and a fixed needle member extending through the nozzle outlet end, the projecting end of such needle being rounded and serving as a work engaging bearing member to definitely space the outlet end of the nozzle from the work and also restricting the outlet opening of the nozzle so that the fluid will flow most efficiently therethrough to provide a continuous stripe of uniform width. With such devices it has heretofore been the practice to secure the needle member in a fixed relation, and as a consequence stoning of the bearing point, to maintain it round, reduces the length of the end projecting from the nozzle to such an extent that capillary attraction between the surface and the nozzle end becomes pronounced and results in a stripe which is wider along portions of its length.

An object of my invention is to provide a striping instrument, of the type above described, in which the needle member is arranged so that a uniform stripe will always result when the device is moved across a surface to be operated upon.

Another object of the invention is to provide a needle member for striping instruments which can be adjusted in its relation with the instrument to properly space the nozzle outlet end from the work so that a uniform stripe can be made.

A further object of the invention is to provide a striping instrument, of the pressure type, in which a needle member is associated with the device so that it can be adjusted lengthwise of the nozzle and in this manner the projecting end can be maintained round and at the same time a uniform distance from the end of the nozzle.

Other objects of the invention will appear from the following description taken in connection with the drawing, which forms a part of this specification, and in which:

Fig. 1 is a medial sectional view of a striping instrument incorporating the invention and shown in operative relation with a surface to be striped;

Fig. 2 is a sectional view taken on line 2—2 of Fig. 1;

Fig. 3 is a fragmentary section of the body portion of the device taken on another line than that on which Fig. 1 is taken and illustrating the fluid circuit from the pump to the nozzle.

Referring now to the drawing by characters of reference, 10 represents the body of a striping instrument which is formed preferably as a solid piece of metal. Extending axially through the body is a bore 11 terminating at one end in a larger bore 12, and communicating with this larger bore 12 is a radially extending bore 13. A handle 14 is screwed into the end of the bore 12 and a fluid container tube 15 is screwed into the radial bore 13 and arranged in open communication therewith. The container 15 is adapted to hold paint or the fluid which is to be dispensed by the device.

A tubular body extension 16 is associated in axial relation with an end of the body and is provided with an end flange 17 over which the flange of a sleeve 18 extends, such sleeve being screwed upon the threaded portion 19 of the body. Pump gears 20 and 21, arranged in meshing relation, are held between the end of the body and the flanged end 17 of the body extension by means of the sleeve. A passage 23 is drilled lengthwise of the body and establishes communication between the radial bore 13 and the pump chamber and another passage 24 is drilled into the pump end of the body and is connected with the axial bore 11 of the body by means of the transversely extending passage 25. Fluid flows from the reservoir 15 through the bore 13 and passage 23 to the pump chamber from which it is moved, by the pump gears, through the passages 24 and 25 to the axial bore 11 in the body.

The axial bore 11 in the body is threaded and a tubular nozzle element 26 is screwed therein. This nozzle element is provided with a restricted outlet opening 27 and provides a conduit through which the fluid is moved from the axial bore 11 to be deposited upon the surface over which the instrument is moved. A needle member 28 extends through the nozzle and is of smaller diameter so that it will permit the passage of fluid through the nozzle. The outer end 29 of the needle is reduced in diameter and is of a size such that it provides a restriction to the flow of fluid through the nozzle so that a desired spread of fluid is deposited as the instrument is moved along the surface to be striped. The projecting end of the needle member is rounded and serves as the device bearing for engaging the surface to be striped. The distance between the end

of the needle and the outlet end of the nozzle must be calculated carefully because when such distance is too great, the fluid being forced through the nozzle will move out in large drops causing an uneven stripe, and when the distance is too small there is a capillary attraction which results in an uneven stripe or a wider stripe than is desired.

Heretofore it was customary to fix the needle element to the interior of the body and when the end thereof was ground or stoned to maintain it more round, the distance between the end of the needle and the nozzle end would be decreased so that eventually the instrument would have to be discarded because of the capillary attraction between the surface and the nozzle during the fluid flow which caused the stripe to be deposited in an uneven width and considerably wider than intended. In order to overcome this difficulty and to materially increase the life of a device of this character, I provide means for adjustably securing the needle, and to this end I press the needle into a securing element 30 which is screwed into the end of the bore 11 adjacent the bore 12. When the handle 14 is removed from the body, the securing member for the needle can be screwed axially so that the distance between the end of the needle member and the outward end of the nozzle can be arranged a definite distance apart. In this manner the proper spacing of the nozzle outlet end from the surface to be striped can be readily provided upon the initial assembly of the device, and can be maintained after each stoning or grinding operation upon the bearing end of the needle to maintain it in round. With the handle removed, the needle and its securing element can be readily removed or assembled axially through the body. It will thus be seen that this simple manner of adjustably securing the needle will materially increase the life of an instrument of this character, and will also insure that a desired width of stripe will be produced upon the surface along which the bearing end of the needle member is moved.

A sleeve 31 surrounds a portion of the nozzle and extends interiorly of the body extension 16. The interior end of such sleeve is fixed to the gear 21 in any suitable manner and the end of the sleeve projecting beyond the body extension is in the form of a wheel 32. Roller bearings 33 are arranged between the outer end of the body extension and the sleeve and are retained enclosed by the roller member. A key 34 extends through the body member and projects into a circular groove 35 formed in the sleeve, such arrangement serving to retain the roller and its sleeve in a definite axial relation with the body extension. A spacer 22 is arranged intermediate the body end and the extension flange and is retained by the pins 36.

The roller 32 is adapted to bear against a beading or raised flange portion adjacent a surface to be striped and when the needle member bears against such surface and the instrument is moved lengthwise of the beading, the roller 32 will be rotated and will transmit such rotation to the pump gears so that fluid is moved through the pump chamber and thence through the nozzle where it will pass by the valve member and will be deposited upon the surface over which the bearing end of the needle member is moved. The rate of fluid flow through the nozzle is commensurate with the speed of movement of the device along the bead, and conse-

quently a uniform amount of fluid will be deposited along the surface irrespective of the speed at which the device is operating and, therefore, a stripe of a uniform quantity and width will result.

It will be seen that the pump will move fluid through the nozzle commensurate with the speed so that a uniform volume is deposited upon the surface to be striped regardless of the speed, and a uniform application of fluid moving through the nozzle in this manner is insured because of the adjustable securing arrangement for the needle member which maintains the nozzle end properly spaced from the work to be striped under all circumstances and without the necessity of replacing any parts.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

What I claim is:

1. In a striping instrument, a body member, a pump associated with the member, said member having a pair of parallel bores one of which is of two diameters and an inlet bore communicating with the pair of parallel bores, a nozzle screwed into an end of the smaller diameter portion of the two diameter bore, a threaded adjusting member screwed into the other end of the smaller diameter portion of the two diameter bore, an outlet passage in the body member leading from the pump to the two diameter bore between the nozzle end and the adjusting member, a needle extending through the nozzle and fixed to the adjusting member, a container fixed to the body in communication with the inlet bore, and a removable handle screwed into and closing the outer end of the larger diameter portion of the two diameter bore.

2. A striping instrument comprising a body member, said member having a pair of parallel bores one of which is of two diameters and a fluid inlet bore communicating with the pair of parallel bores, a nozzle screwed into an end of the smaller diameter portion of the two diameter bore, an adjusting member screwed into the other end of the smaller diameter portion of the two diameter bore, a connection between the two parallel bores communicating with the two diameter bore between the nozzle end and the adjusting member, a needle extending through the nozzle and fixed to the adjusting member, a container fixed to the body in communication with the parallel bore which communicates with the two diameter bore, and a removable handle screwed into and closing the outer end of the larger portion of the two diameter bore, said handle and said container being interchangeable in their relation with the body.

3. A striping instrument comprising a body member having a bore extending therethrough, a rigid nozzle threaded into one end of the bore, a needle extending through the nozzle, an end portion of the needle forming a work engaging means and a restriction for the flow of fluid from the nozzle outlet end, an axially adjustable member screwed into the bore, said member being fixed to the inner end of the needle, fluid feeding means connected with the inner end of the nozzle, and means closing the other end of the bore remote from the nozzle, the axial

adjustment of said member regulating the distance between the work engaging end of the needle and the outlet end of the nozzle without changing the rate of fluid flow from the nozzle.

- 5 4. In a striping instrument, a body having a bore extending therethrough, a nozzle extending into the bore and secured to the body, a needle member in the nozzle regulating flow therethrough, a needle carrier axially adjustable in the bore beyond the nozzle, said carrier being

adjustable through the end and closing an intermediate portion of the bore, fluid feeding means in the body in communication with the nozzle and the bore beyond the carrier including an opening, a handle and a container, said handle and said container being interchangeable and attached to the body to engage one in the end of bore beyond the carrier and the other in the body opening.

EARL M. BARDEN. 10

CERTIFICATE OF CORRECTION.

Patent No. 1,994,238.

March 12, 1935.

EARL M. BARDEN.

It is hereby certified that error appears in the printed specification of the above numbered patent requiring correction as follows: Page 2, second column, line 74, claim 3, for "other" read outer; and that the said Letters Patent should be read with this correction therein that the same may conform to the record of the case in the Patent Office.

Signed and sealed this 28th day of May, A. D. 1935.

Leslie Frazer

(Seal)

Acting Commissioner of Patents.
